UNITED STATES PATENT OFFICE

FREDERIC C. WINKLER, OF LAKEWOOD, OHIO, ASSIGNOR TO WESTINGHOUSE ELECTRIC
& MANUFACTURING COMPANY, A CORPORATION OF PENNSYLVANIA

DESIGN FOR A GLOBE

Application filed June 11, 1931. Serial No. 40,165. Term of patent 7 years.

To all whom it may concern:

Be it known that I, FREDERIC C. WINKLER, a citizen of the United States, residing at Lakewood, in the county of Cuyahoga and State of Ohio, have invented a new, original, and ornamental Design for a Globe, of which the following is a specification, reference being had to the accompanying drawings, constituting a part hereof:

Fig. 1 is a side elevational view of my globe, and

Fig. 2 is a bottom plan view of the globe shown in Fig. 1.

I claim:

The ornamental design for a globe substantially as shown.

In testimony whereof, I have hereunto subscribed my name this 4th day of June, 1931.

FREDERIC C. WINKLER.
